UNITED STATES PATENT OFFICE.

JOHN GIBBONS, OF WEST TROY, NEW YORK, ASSIGNOR TO THE UNION HARDWARE MANUFACTURING COMPANY, OF SAME PLACE.

HALTER-TRIMMING.

SPECIFICATION forming part of Letters Patent No. 300,461, dated June 17, 1884.

Application filed December 28, 1883. (No model.)

To all whom it may concern:

Be it known that I, JOHN GIBBONS, of the village of West Troy, county of Albany, State of New York, have invented new and useful 5 Improvements in Halter-Trimmings, of which the following is a specification.

My invention relates to that class of devices which are used to connect the end of the halter-strap to the latter at a sufficient distance 10 from the end to form the halter-loop by means of a snap-hook on the rope and an eye on the device.

In the accompanying drawings, forming a 15 part of this specification, there are shown two figures illustrating my invention, with the same designation of parts by letter-reference used in all of them. Of these two illustrations, Figure 1 shows the fastening device attached to a rope, and in connection with a 20 snap-hook forming the lead-loop of a halter. Fig. 2 shows a perspective of the device as detached from the rope.

The several parts of the device, and those 25 of a halter with which it connects, are designated by letter-reference, and their function explained as follows.

The letter S indicates the halter-strap; L', the halter lead-loop, and L² the tether end of the rope.

The letter B designates a snap-hook connecting with an eye, E, on the end of the fastening device, and I designates the latter. This fastening device consists of the two parallel side bars, B' B², a central semicircular strap, 30 J, connecting with said bars, and the two semicircular straps C' C², which connect with 35 the ends of the bars. All these parts are made with surfaces that are circumferentially coin-

cident, and which would, if circularly continued, produce a cylinder. The central strap, 40 J, is made with the spur D, that is projected outwardly from the interior surface of the strap, and the end strap C² is made with the projecting connecting-eye E. With the device thus made, when a rope is passed through 45 it, and the spur is forced into the rope thus placed, the latter is firmly held in place, and a snap-connection made with the fastener that will be a stable one, while the device will be attached to the rope without having the rope 50 tortuously threaded through the fastener, as is the case when a plate having a series of openings is used. The fastening device thus described is preferably made of malleable cast metal.

Having thus described my invention, what I claim, and desire to secure by Letters Patent, is—

As an improved article of manufacture for halter-trimmings, the within-described device, in combination, consisting of the parallel bars B' B², made with interior concave surfaces, the central semicircular strap, J, connecting with said bars, the spur D on the interior of said strap J, the end semicircular 60 straps, C' C², connecting with said bars, and the eye E on the end strap C², constructed and arranged as herein shown.

Signed at the city of Troy this 19th day of December, 1883, and in our presence whose 70 names were hereto by us written.

JOHN GIBBONS.
